TARGET

Mitchell G. Rosengarten, Philadelphia, Pa.

Application June 17, 1936, Serial No. 85,663

1 Claim. (Cl. 273—35)

This invention relates to targets suitable for use in connection with games or exercises in which a relatively soft, light disc-shaped missile is driven against the target, and more particularly to a 5 novel combination of a target and a coacting missile-disc. In such games or exercises it is desirable that the missile shall adhere to the target in order that the part of the target struck may be better observed and scored. According to my invention the target is a backing faced with projecting points or bristles, as for example, the clothing used for carding machines in the textile industry.

Clothing for cards customarily comprises a 15 backing with short bristle wires supported in such relation to the backing as to project in parallel relation a certain distance from the face of the backing. I have discovered that the wires which thus project out from the face, and which in card clothing perform the usual carding function, are 20 particularly adapted to receive and hold in place a suitable missile driven against them; and according to my invention, a target for this purpose is made of card clothing, or of a suitable backing 25 with projecting wire points, and mounted or supported so that the face of the card clothing forms the face of the target.

I will illustrate and describe my invention as 30 applicable to a game (called "Clickit") simulating to some extent the game of golf, and in which a cardboard missile about the size of a golf ball is driven by a golf club against such a target. The target is marked with circles and it being the object of the player to drive the missile so as to 35 hit the center of the target, it is desirable that the missile shall be retained wherever it may strike the target in order that the deviation of its flight from that which is desired may be observed. But although I thus show and describe this application 40 of my invention, it must be understood that the scope of the invention is broader than this and not dependent upon the particular game played.

In the accompanying drawing, Fig. I represents 45 in elevation a target with suitable supporting devices constructed according to my invention.

Fig. II is a partial vertical section along the line II—II of Fig. I.

Fig. III is a similar section along the line III—III of Fig. I; and

Fig. IV shows in vertical section a variant construction.

The frame 1 of the target may be of any desired shape and made of any suitable material, but is preferably wood or metal. For purposes of firm 55 support a thin back plate 2 extends from edge

to edge of the frame and is secured to it. Upon this metal plate 2 is placed a backing 5 which supports wire points 6 suitably embedded or enmeshed in said backing. The backing 5 may be of fabric, rubber or leather, or other suitable material. The wires 6 are small, slightly flexible, and project from the face of the backing 5 sufficiently to receive and support the missile as it strikes. This missile may be a circular disc 7 of cardboard. In the game to which I have referred 10 it is of the diameter of a golf ball and is driven by a stroke from a golf club upon its periphery. If properly driven it flies straight to the target until the edge of the missile hits the face of the target. The cardboard is of sufficient softness to 15 enable the point of the wire or wires struck to penetrate the cardboard and thus support it or, should the edge of the missile pass between wires or lines thereof, it will nevertheless be supported by the resiliency of the wires for they are set in rows sufficiently close together to require deflection when the missile passes between them. Thus the plain, unbristled disc 7 is held by engagement of its margin with or amongst the target bristle wires 6. I have found that a missile of cardboard 20 39 thousandths of an inch thick works well in combination with card clothing in which the wires are set 33 thousandths of an inch apart.

It is preferable, but not necessary, that the 25 projecting wires 6 be bent as shown in Fig. II of the drawing and that the target be so placed that the bend of the wires is toward the ground. The missile 7 is then driven upward from the ground and in its rising flight is the better intercepted and held by or impaled upon the metal 30 points in case they be thus bent; but this is a matter of convenience and not absolutely necessary to my invention.

In Fig. II the surface of the target is covered 35 by card clothing of a well known variety with wire staples penetrating a backing. In Fig. IV the backing 5 is penetrated by pointed brads or pins 8, the heads 9 of which lie between the backing and the plate 2.

As shown, the target is supported by a pair of 40 three sided or U-shaped yoke-like standards or legs 10 connected at their ends to the lower corners of said target by friction hinge devices 11. Each of these friction hinge devices 11 includes, as shown in Fig. III, a headed pivot bolt 12, the 45 nut 13 of which constitutes an adjustable abutment for a helical spring 14 which bears upon a hinge arm 15 secured to the side edge of the target and thus holds the interpivoted parts under 50 frictional restraint. By virtue of being shaped 55

and proportioned as shown, the legs or standards 10 can be folded to surround the frame of the target, thus rendering the device compact for transportation or boxing.

- 5 Although the missile which I have described is a disc of cardboard, other missiles may be used, provided the series of short wires thus projecting and mounted are capable of retaining the missile in place. The size and marking of the target will 10 depend upon the nature of the game played and of the score desired, and form no part of my invention.

Having thus described my invention, I claim:

Game apparatus comprising a plain cardboard missile-disc, adapted to be propelled by a stroke of a golf-club against its edge, and a target therefore faced with projecting bristles of such length and resiliency and so spaced as to impale, receive amongst them, and hold the margin of the plain cardboard missile-disc itself, and adapted thus to retain and support it where it strikes. 5

10 MITCHELL G. ROSENGARTEN.
